UNITED STATES PATENT OFFICE.

SAMUEL B. BARTHOLOMEW, OF SPRINGFIELD, MASSACHUSETTS.

SEWING-MACHINE SHUTTLE.

SPECIFICATION forming part of Letters Patent No. 269,998, dated January 2, 1883.

Application filed June 6, 1882. (No model.)

To all whom it may concern:

Be it known that I, SAMUEL B. BARTHOLOMEW, a citizen of the United States, residing at Springfield, in the county of Hampden and State of Massachusetts, have invented new and useful Improvements in Sewing-Machine Shuttles, of which the following is a specification.

This invention relates to an improved tension for the thread of sewing-machine shuttles, having for its object the security of the thread when in its operative position in the shuttle, together with facility of adjustment of the thread to said position. This I accomplish by means as fully hereinafter described, and illustrated in the accompanying drawings, in which—

Figure I is a rear side view, in partial section, of a shuttle having my improvements. Fig. II is the same as Fig. I, with the bobbin and tension-spring removed; and Fig. III is a plan view with the bobbin removed.

B is the front plate of a shuttle having its rear face shown in Figs. I and II.

C is the rib framing and seating the bobbin D, formed and secured in the shuttle in the usual way.

I is a spring, secured at one end to the inner face of the plate B, and forming the tension-spring.

30 To construct my improved tension, an eye or opening, h, is formed in the spring I, as shown in Fig. I, to be in prolongation with an opening, f, in the plate B. While the opening h has a continuous edge, the opening f is connected by a passage, c, with the outside. The spring I is also provided with the eye g, and is pointed as at u, to lead the thread through surfaces v o from the outer edge of the spring to the eye g from the inner edge, as shown in Fig. I.

In the operation of threading, the end of the thread b is passed through the hole h in the

tension-spring I and continued through the opening f to the front face of plate B, from which position it is grasped by the hand to have the thread borne up through passage c against the unbroken surface of spring I, to move between the plate B and spring I and follow the edge of the spring to the eye g, at the end of which operation it is in the position shown in Fig. I; and it will be seen that, as entirely inclosed by opening h, it is impossible for an unbroken thread to become detached from the spring I. In practice I connect the eye h with an auxiliary one, placed at any convenient point in the spring, by means of the channel m, having a direction from eye h approximating to that taken by the thread when moved along the spring from the opening c, and I bevel the outer edges of the opening c, as indicated in Figs. II and III, to remove any angle which might catch the thread in moving along the edge of the shuttle, as well as to facilitate the movement of the thread in "threading." After the thread b is entirely inclosed by the spring in being passed through eye h, it is only one motion to complete the threading.

What I claim is—

1. In a sewing-machine shuttle, the combination and arrangement, substantially as shown and described, of the tension-spring I, having eye h and eye g, with plate B, having eye f in prolongation of eye h, and provided with an outlet, c, for the purpose as set forth.

2. The combination and arrangement with plate B, having eye f therein, with its outlet c, of spring I, provided with eyes h and h', and connecting channel m, continuously inclosed, and with eye g and guiding-surface leading thereto, substantially as shown and described.

SAMUEL B. BARTHOLOMEW.
